UNITED STATES PATENT OFFICE

HEINRICH KÖNEMANN, OF MUNSTER, GERMANY

APPARATUS FOR RECORDING ELECTRIC ALTERNATING CURRENTS BY MEANS OF A VOLTAIC ARC

Application filed October 20, 1928, Serial No. 314,307, and in Germany October 29, 1927.

The devices for improved recording of electric alternating currents by means of a voltaic arc such as set forth in my copending application, Serial No. 277,678, filed May 14, 1928, are further developed according to the present invention for the purpose of obtaining more exact recording.

The present invention consists in arranging in the said device, a means which produces a proportionality between the form of the alternating current and the emitted light of the arc.

In order that an electric current shall pass through a gas, a definite amount of ionization of the gas particles between the electrodes is necessary; and this amount of ionization is proportional to the current intensity. If, therefore, the amplified alternating current of a microphone, for example, is superimposed upon the direct current of the arc, then the degree of ionization of the gas particles between the electrodes must fluctuate in periodicity with the superimposed alternating current. Since the light which serves for the photographic recordation of the sound is dependent upon the degree of ionization, it is a requirement for proper recording that the ionization of the arc shall increase and decrease in exact correspondence with the superimposed alternating current from the microphone.

However, if the electrodes are very hot, then their high temperature will cause gas particles near them to remain ionized although the current has decreased, or in other words the emitted light from the arc is no longer at this time proportional to the superimposed alternating current.

A simple method for the purpose of maintaining the desired proportionality consists in keeping the temperature of the electrodes low. The ionization of the gases in the path of current can then follow the fluctuations of the current passing through in a better manner, whereas at a higher temperature of the electrodes, the latter keep the gas particles in their proximity ionized for a longer time.

The consequence of this is that the electrical fluctuations which correspond to the sounds are more easily transformed into

luminous fluctuations; in other words, with oxidized electrodes the photograph of the sounds is much better formed and much richer in lines than that made without metal oxides.

To keep the temperature low, metal oxides may be employed for the electrodes. The electrodes themselves may be oxidized or they may be covered with an oxide. The oxide coated electrodes give off the electrons more easily than the simple metal. A voltaic arc employing oxide coated electrodes does not require so great a current intensity as a lamp employing simple metallic electrodes, and hence the oxidized electrodes do not require so high a temperature. The ionization in the gas therefore corresponds to the current intensity being transmitted across the gap, and substantially no auxiliary or heat ionization occurs. Therefore, with the change of the current intensity, the ionization changes in a like ratio and in the same direction, without any damping or deadening of the immediate response by the effect of the heat-ionized gas particles, so that the ionization at any instant exactly corresponds to the current intensity of the direct current as modulated by the alternating current. It is easily seen from the strength of the light in such a case, (all other conditions being the same), that the temperature of the oxide electrodes is lower than in an arc between electrodes of pure metal.

On the accompanying drawing is represented a recording apparatus for sound films according to this invention, in one form of execution; which drawing shows:

Figure 1, a circuit diagram.

Fig. 2, a detail of the recording lamp in vertical section.

Fig. 3, a detail of the ends of the electrodes, provided with an oxide coating, in longitudinal section on a larger scale than in Fig. 2.

The tungsten arc lamp L (Fig. 1) is supplied from the direct current mains through an intercalated resistance W_1 and a choke coil D. The currents from the microphone M are then superimposed upon the direct current by means of the transformer T. The resistance W_2 serves as a steadyng resistance for this alternating current. The condenser

C opens a path for the alternating current while it closes this path to the direct current. The choke D keeps the alternating current away from the direct current mains. The 5 luminous fluctuations in the lamp L are fixed by this apparatus upon the passing film F.

The tungsten arc lamp L is represented in detail in Fig. 2. The electrodes 1 and 2 have a voltaic arc 7 burning between them; these 10 electrodes being held in the holders 3 and 4 supported in the glass foot 5, within the glass vessel 6 which shuts off the interior of the lamp with respect to the atmosphere. The electrodes 1 and 2 are covered with oxide as 15 may be distinctly seen in Fig. 3.

In operation, the intensity of the volatic arc 7 in the lamp L fluctuates in accordance with the superimposed or modulating alternating currents from the microphone M in 20 their effect upon the direct current supplied to this arc lamp. By employing the metal oxides to coat the electrodes 1 and 2, the temperature of maintaining the arc is maintained below the point of substantial ionization 25 of the gas employed within the enclosing vessel 6.

Claims:

1. The method of recording sound by means of a voltaic arc operating between 30 oxide coated electrodes in a gas, which comprises passing a direct current therethrough to produce the voltaic arc at a temperature below the point of substantial heat ionization of the gas, and modulating the direct current 35 by a sound current whereby to vary the light intensity of the arc, and recording the light fluctuations of the arc.

2. An apparatus for recording sound, comprising a voltaic arc lamp including tungsten 40 electrodes having a coating of metallic oxide and a gas containing envelop surrounding said electrodes, a source of direct current to operate said lamp at a temperature below that of substantial heat ionization of the gas, 45 and means to modulate the light intensity of the arc according to the sound intensity and including a microphone and circuits for connecting the same to the said electrodes.

3. An apparatus for recording sound by 50 means of a voltaic arc modulated in intensity by an alternating electric current and having tungsten electrodes, including a coating of metal oxide on the tungsten electrodes to make the light emission of the recording arc 55 more conformable to the alternating current superimposed to the direct current of the arc, and a source of current to heat said coatings to a temperature below that of substantial heat ionization.

60 In testimony whereof I have signed my name to this specification.

HEINRICH KÖNEMANN.
